YARN ASSEMBLY

David Tamm, Detroit, Mich.

Application June 20, 1946, Serial No. 673,116

6 Claims. (Cl. 2-273)

1

This invention relates to yarn assemblies and more particularly to prefabricated strips for use in making pile fabrics such as hooked rugs and the like.

It is an object of this invention to provide an improved yarn assembly of the above indicated type which is simple and economical of manufacture and which may be easily and quickly mounted on a rug backing or other background to which it is to be attached.

Another object of the present invention is to provide a yarn assembly in which the yarn may be readily mounted upon the supporting element and which assembly may be packaged and stored in a minimum of space.

It is a further object of the present invention to provide a yarn assembly which greatly facilitates the manufacture of pile fabrics and substantially decreases the time and labor required in the production thereof.

It is a further object of the present invention to provide an improved yarn assembly for the manufacture of pile fabrics which permits the rapid manufacture of such fabrics even though a considerable color scheme is involved in the final product.

Other and more detailed objects of the present invention will become apparent from an examination of the accompanying drawing in which like reference characters designate like parts throughout and wherein:

Figure 1 is a broken elevational view of a yarn assembly embodying features of the invention;

Fig. 2 is an end view of the structure illustrated in Fig. 1;

Fig. 3 is a broken elevational view of the yarn assembly of Fig. 1 in the compressed or flattened condition;

Fig. 4 is an end view of the structure illustrated in Fig. 3;

Fig. 5 is an elevational view showing a plurality of yarn assemblies secured to the backing of a rug or the like;

Fig. 6 is a view of the structure illustrated in Fig. 5 after the looped end of yarn and supporting element have been severed;

Fig. 7 is a view of the structure illustrated in Fig. 6 after the severed supporting element has been removed, and

Fig. 8 is a broken plan view of a rug construction using the yarn assemblies of the present invention and illustrating how a color pattern may be worked thereinto.

Referring to the drawing, the yarn assembly 8 comprises a flat striplike supporting element 10

2

which carries a strip of mucilage or other suitable adhesive 12 which extends longitudinally of the element 10 and is disposed in close proximity to one longitudinal edge thereof, as is best seen in Fig. 3. The element 10 may be formed of any suitable material and in the preferred embodiment is formed of paper. This paper strip 10 supports a continuous length of yarn 14 which is wound about the paper in a series of continuous helical loops each of which engages the adhesive 12 which serves to hold the yarn in place on the strip.

While it will be apparent that the yarn 14 may be wound about the element 10 while it is in the flattened condition illustrated in Figs. 3 and 4, it has been found easier and quicker to support the paper 10 in the shape of a tube or cylinder, as illustrated in Figs. 1 and 2, and to rotate it while winding the yarn 14 in place. When the yarn 14 has been wound upon the tube, the tube and yarn together may then be compressed to the flat shape illustrated in Figs. 3 and 4, care being taken that in so doing the mucilage strip 12 is disposed in close proximity to one of the longitudinal edges thereof.

It will be appreciated that the yarn assembly, while having a particular utility in the manufacture of rugs, is capable of numerous varied applications in the production of pile fabrics of widely varying types.

The yarn assembly 8 is used in the following manner. The assembly 8 is placed on a piece of burlap or other suitable backing material 16, and is sewed to the backing along the mucilage strip 12. The assemblies 8 are secured to the backing 16 in overlapping relation in shingle fashion, as illustrated in Fig. 5. A sharp knife is then inserted between the two thicknesses of the supporting element 10 and it is cut along the edge opposite to that secured to the backing 16. By this same operation, the loops of yarn are cut at the point where they pass over this edge of the element 10. The yarn assemblies 8 illustrated in Fig. 6 have been cut in this manner. In sewing the yarn assembly to the backing 16, the supporting element 10 is perforated by the sewing needle and may readily be removed by tearing along the line of this perforation, leaving only the yarn of each yarn assembly extending upwardly from the backing 16, as illustrated in the lower part of Fig. 7.

This yarn assembly 8 is especially adapted for working color patterns into hooked rugs and similar pile fabrics, since the strips may be made up in numerous colors of yarn and the color may

be changed as desired by merely cutting off the assembly being used and continuing with an assembly of the desired color. When a strip is thus cut off, the adhesive 12 prevents the loops on the strips from coming unwound or being displaced. This construction thus permits the color to be readily changed as frequently as desired. In the rug portion illustrated in Fig. 8, a diagonal purple line illustrated at 28 has been produced by changing the color as described above. It will be understood that any desired pattern may be produced in this manner.

As above indicated, the yarn may be wound upon a flat supporting element, thus eliminating the flattening operation found desirable when an initially cylindrical element is employed. A flat strip of paper or light cardboard may be used. In either event, whether an initially flat element is employed, or whether an initially cylindrical element is used and flattened during preparation of the assembly 8, it will be apparent that the yarn may be cut without cutting the supporting element, and the latter may then be removed by tearing along the perforations formed therein by the sewing operation.

While only one specific embodiment of the invention has been illustrated and described in detail, it will be apparent to those skilled in the art that numerous modifications and changes may be made without departing from the spirit of the invention and from the scope of the appended claims.

What is claimed is:

1. A yarn assembly adapted for the production of pile fabrics comprising a longitudinally extending supporting element formed of a material which is easily torn when perforated by a sewing needle, a strip of adhesive material provided along the longitudinal length of said element, and a continuous length of yarn wound upon said element in a series of adjacently disposed loops each of which engages said adhesive material and is held in place thereby.

2. A yarn assembly adapted for the production of pile fabrics comprising a longitudinally extending tube formed of a material which may be readily cut and easily torn when perforated, a strip of adhesive material supported on and extending along said tube, and a continuous length of yarn wound upon said tube in a series of adjacently disposed loops each of which engages said adhesive material and is held in place thereby.

3. A yarn assembly adapted for the production of pile fabrics comprising a longitudinally extending flat strip element formed of a material which

may be readily cut and easily torn when perforated, a strip of adhesive material supported on and extending along said element, and a continuous length of yarn wound upon said element in a series of adjacently disposed loops each of which engages said material and is held in place thereby.

4. A yarn assembly adapted for the production of pile fabrics comprising a longitudinally extending paper tube, a strip of adhesive material supported on and extending along said tube, and a continuous length of yarn wound upon said tube in a series of adjacently disposed loops each of which engages said adhesive material and is held in place thereby.

5. A yarn assembly adapted for the production of pile fabrics comprising a longitudinally extending supporting element formed of a material which may be readily cut and easily torn when perforated, a strip of adhesive material supported on and extending along said element, and a continuous length of yarn wound upon said element in a series of adjacently disposed loops each of which engages said adhesive material and is held in place thereby, said supporting element being adapted to permit said yarn to be secured to a backing material by sewing through said yarn and said supporting element.

6. A yarn assembly adapted for the production of pile fabrics comprising a longitudinally extending supporting element formed of a material which may be readily cut and easily torn when perforated, a strip of adhesive material supported on and extending along said element, and a series of adjacently disposed loops of yarn each of which engages said adhesive material and is held in place thereby, said supporting element being adapted to be supported in tubular shape while said yarn is wound thereabout and then compressed to a flat strip shape.
